CLAIM

The ornamental design for a canopy for light fixtures, as shown and described.

DESCRIPTION

FIG. 1 is a perspective view of the canopy for light fixtures showing my new design;

FIG. 2 is a front elevational view thereof, the rear elevational view being a mirror image;

FIG. 3 is a right side elevational view thereof, the left side being a mirror image; and

FIG. 4 is a bottom plan view thereof. The top plan view being plain and devoid of any ornamentation.

FIG. 5 is a perspective view of a second embodiment on my new design;

FIG. 6 is a front elevational view of FIG. 5, the rear elevational view being a mirror image;

FIG. 7 is right side elevational view of FIG. 5, the left side elevational view being a mirror image;

FIG. 8 is a bottom plan view of FIG. 5; The top plan view of the second embodiment is plain and devoid of any ornamentation;

FIG. 9 is a perspective view of a third embodiment on my new design;

FIG. 10 is a front elevational view of FIG. 9, the rear elevational view being a mirror image;

FIG. 11 is right side elevational view of FIG. 9, the left side elevational view being a mirror image; and,

FIG. 12 is a bottom plan view of FIG. 9. The top plan view of a third embodiment is plain and devoid of any ornamentation.

The broken lines in the drawings are included for the purpose of illustrating portions of the article that form no part of the claimed design.

1 Claim, 6 Drawing Sheets
